UNITED STATES PATENT OFFICE.

JACOB HEERMANS, OF NASSAU, NEW YORK.

DESIGN FOR A STOVE.

Specification forming part of Design No. 153, dated October 2, 1847.

To all whom it may concern:

Be it known that I, JACOB HEERMANS, of Nassau, in the county of Rensselaer and State of New York, have invented or produced a new and useful ornamental Design for an Air-Tight Cooking-Stove; and I do hereby declare that the accompanying drawings are full and accurate delineations of my said design.

Figure 1 is a perspective view to show the general form; Fig. 2, a side view, upon a larger scale, to exhibit the detail of ornament; Fig. 3, the front, and Fig. 4 the rear.

Where only a portion of the ornament is represented in the panels, the remaining part is similar to and symmetrical with that represented.

The ornament shown in the panel *a a*, Fig. 4, is repeated in the panels marked *b b b*, Fig. 3, and *c c*, Fig. 4.

What I claim as my invention, and desire to secure by Letters Patent, is—

The combination and arrangement of ornamental forms and figures represented in the accompanying drawings, and forming an ornamental design for an air-tight cooking-stove.

JACOB HEERMANS.
